UNITED STATES PATENT OFFICE.

FRANK L. SESSIONS, OF COLUMBUS, OHIO, ASSIGNOR TO THE JEFFREY MANUFACTURING COMPANY, A CORPORATION OF OHIO.

ELECTRIC LOCOMOTIVE.

1,123,602.

Specification of Letters Patent.

Patented Jan. 5, 1915.

Application filed June 2, 1908. Serial No. 436,309.

To all whom it may concern:

Be it known that I, FRANK L. SESSIONS, a citizen of the United States, residing at Columbus, in the county of Franklin and State of Ohio, have invented certain new and useful Improvements in Electric Locomotives, of which the following is a specification, reference being had therein to the accompanying drawing.

10 This invention relates to electric "gathering" locomotives used particularly in mines to collect the coal or ore cars from the various rooms and parts of the mine in which the coal or ore is being cut and loaded.

15 Cable reeling devices are commonly used upon such locomotives to enable the locomotive to reel up and pay out its own conductor and thus traverse parts of the mine which are not equipped with permanent trolley wire installations. The trackage leading from the main entry through side entries and into the rooms which are being worked is a temporary construction and often consists of wooden rails, or iron rails which it

20 would be inconvenient and uneconomical to electrically bond. Under these circumstances it is necessary for the flexible cable which is carried by the reel to be made of two insulated conductors, the fixed ends of

25 which are attached at the main entry to the trolley wire and to the track rail respectively. With this arrangement the two conductors form a complete circuit from the trolley wire to the locomotive motor and

30 back to the main entry rail as the locomotive moves away from the main tracks into the rooms and the rails in the rooms may be of wood or steel rails without bonding or fish-plates. Two kinds of double conductor

35 cables have been used, one consisting of two insulated wires, laid side by side, and suitably bound together, and the other consisting of two conductors arranged concentrically and insulated from each other, the

40 outer conductor being a cylindrical shell of wires helically interlaced. With the former cable, *i. e.*, the flat duplex cable, its non-cylindrical form causes it to twist and wind unevenly upon the reel, and in some instances to wind so unevenly as to cause it

45 to strike parts of the metal frame of the locomotive adjacently surrounding the reel so as to wear off the insulation and ground the

circuit. In mine locomotives it is necessary to economize space in every possible way and 55 the reel and adjacent parts of the locomotive must be arranged very compactly. It therefore happens that if the cable does not wind in perfectly even uniform layers back and forth upon the reel, the trouble just described is met with.

With the concentric duplex cable, there is a tendency after it has been wound and unwound repeatedly for the conductors to become of different lengths. The continued 65 reeling and unreeling of the cable causes a crimping of one or both of the conductors in their sheaves, and a corresponding kinking of the cable throughout its entire length. When thus distorted, it is almost impossible 70 to straighten the cable or spool it evenly upon the reel. Furthermore, there is always the tendency in these duplex cables of either kind for the conductors to come into contact with each other because of poor insulation 75 or because of the insulation becoming worn and thin by long use. It is the object of this invention to overcome these difficulties by using two reels upon the locomotive, each reel carrying a single conductor cable. 80 While two cables could be wound upon one reel, this arrangement would be an undesirable one inasmuch as one of the cables might stretch in use more rapidly than the other, and cause uneven winding. It is also 85 desirable to provide separate spooling devices, one for each cable since the cables may not wind at the same speed, each spooling device being driven across the face of its drum at a speed proportional to the number 90 of revolutions of that particular drum.

Another advantage of my invention lies in the fact that the single conductor cables are ordinarily more apt to be carried in stock by electrical supply houses. Ease of 95 repair is another consideration leading to the employment of the single conductor cable.

Another object of my invention is to provide improved power transmitting devices 100 and clutch mechanism between the source of power, such as the wheel axle, or the motor shaft, and the cable reel.

Other objects are to provide improved electrical connections, improved arrangement and construction of the spooling de-

vice and improvements in the general arrangement of the parts of the cable reeling mechanism.

Figure 1 is a side elevation of a locomotive embodying my invention. Fig. 2 is a plan view of the same. Fig. 3 is an end view of the cable reel and driving connections. Fig. 4 is a central, longitudinal horizontal section of the cable reel along lines 4-4 of Fig. 3. Fig. 5 is an enlarged central, longitudinal vertical section of the reeling mechanism along the line 5-5 of Fig. 3. Fig. 6 is a perspective view of the cable reeling mechanism. Figs. 7 and 8 are detail perspective views showing the electrical contact devices within the reel together with adjacent parts. Figs. 9 and 10 show the two kinds of disks used in the friction clutch. Fig. 11 is a sectional view of the shaft 67 and related parts.

In the drawings 1-1 indicate the side frame pieces and 2-2 the end frame pieces of the locomotive. The forward pair of the locomotive wheels 3-3 are driven by the motor 4, which carries the pinion 5 adapted to engage with the gear wheel 6 upon the wheel axle 7.

Upon the forward end of the locomotive, are mounted the two similar drums 8 and 9, on which of each is wound a flexible insulated electric conductor cable 10, 11. The cable on the left hand drum 8 is designed to be attached to the trolley wire in the main entry, and the cable on the right hand drum 9 is designed to be connected to the negative side of the circuit, that is, to the track rail in the entry. These drums are revolvably mounted upon the shaft 17, both shaft and drums being carried by the bearing supports 42 secured to the locomotive frame parts in a manner to be hereafter described.

The reels 8 and 9 are made up respectively of the spooling cylinders 8^a and 9^a, the end flanges 12-12 and 13-13, the annular webs 12^a and 13^a and the hubs 14 and 15.

Between the hubs 14 and 15 and the shaft 17, are located the bearing linings 16. Keyed to the shaft 17, and mounted between the inner ends of the two reel hubs is the sleeve 18, upon which, in turn, is keyed the sprocket wheel 20, adapted to be driven, in a manner to be presently described, by the chain 21.

Against the lateral annular faces of the sprocket wheel 20, the friction disks 24, 24^a (see Figs. 9 and 10) are pressed, by means of the plates 25 and springs 26, each of the latter being positioned at one end in sockets in the corresponding plate 25 and abutting at the other end against one of the adjustable collars 27, which are screw threaded upon the sleeve 18. These friction disks 24 and 24^a, as clearly shown in Figs. 9 and 10, are of two kinds, arranged alternately, those of one set being notched around their outer edges to engage and be held stationary by

the rib keys 28, cast upon the inner surface of the reel spools, and those of the other side being internally notched to fit the keys 19, by which the sprocket wheel 20 is fixed in position upon the sleeve 18.

It is evident that by this construction and arrangement of parts, the revolution of the sprocket wheel 20 will cause the drums 8 and 9 to wind the cables 10 and 11, maintaining in them a predetermined tension, practically constant in degree, each cable being wound independently of the other.

The conductor ring 30, provided with a suitable connector 31 to receive the end of the cable 10, is mounted upon the insulating ring 29 which is secured by screw bolts to the outside face of the web 12^a of the positive drum 8.

To the inner face of the bearing support 42, is bolted the insulating ring 36 carrying the stationary conductor ring 35, which is provided with connector 37 for the end of the wiring which leads to the motor. The contact ring 32, by means of the springs 34 and the rods 33 rigidly secured to the contact ring and slidably engaging sockets in the conductor ring 35, is mounted to be held yieldably in contact with the conductor ring 30.

The end of the negative cable 11 is attached to the web 13^a of the drum 9 by the screw 38 and the electric circuit is completed to the negative terminal of the motor by means of the metallic frame parts of the reel and locomotive.

The hubs 14 and 15 are each extended outward to form journals 39, 39, which turn in the bearings 41, 41, of the bearing supports 42, 42. Bearing bushings 40-40 are interposed between the journals 39-39 and the bearings 41-41. The bearing supports 42-42 are attached to the yoke plates 44, 44, which span the cross-bars 45, 46, supported by the foot pieces 47, 47, bolted to the locomotive side frames.

The lubrication of each journal 39 is accomplished by means of an oil box 48 in the top of the bearing support 42, from which the oil hole 49 leads downward connecting with the oil groove 50 in the bearing bushing 40 and with one or more oil holes 51 in the journal 39, communication being thus established with the bore of the hubs 14 and 15.

The open ends of these hubs are closed by the plugs 52, which are keyed in place. On the outer ends of the plugs are formed the pinions 53, each of which meshes with a gear wheel 54 on a stud pin 56 mounted in the boss 57 on the corresponding bearing support 42. Each of the stud pins 56 also carries a sprocket wheel 55 secured to the corresponding gear wheel.

The double spooling device, the general construction of which is similar to the well

known spooling mechanism used with cable reels, is arranged adjacent to the reel drums. The rods 60 and 61 rotate in bearings in the brackets 72, which constitute extensions of the yoke plates 44. Each of these rods is provided at one of its ends with a sprocket wheel, one sprocket wheel at each side of the machine, these sprocket wheels 62 being connected by the chains 63 with the sprockets 55. Each of these rods 60 and 61 has formed thereon a compound screw thread for one-half of its length, the threaded half of one rod lying opposite to the smooth half of the other rod.

15 A follower guide 59 reciprocates upon these rods across the face of each of the drums and is given greater rigidity by means of the extension 59^a which embraces the cross-bar 46. By this construction each 20 spooling guide is always in the same relative position with respect to its corresponding drum for any particular stage of the operation of winding or unwinding, and there is no positive power-transmitting 25 connection between the two spooling mechanisms.

In bearing boxes 74 at the ends of bracket arms 73, which extend rearwardly from and are constructed rigidly with the motor casing 30 and frame, is journaled the counter-shaft 67 which is positively geared to the gear wheel 6 on the axle 7 by the pinion 66.

Sleeved upon this counter-shaft 67 is the sprocket wheel 22 connected to the sprocket 35 wheel 20 upon the reel shaft by chain 21. This sprocket wheel 22 is prevented from rotating when the reels are paying out the cable by means of the ratchet wheel 64 and spring-pressed pawl 65 engaging therewith 40 and pivotally mounted upon parts rigidly connected to the motor frame and casing.

Between the sprocket wheel 22 and the gear wheel 66 is interposed the uni-directional drive clutch 75, composed of spiral 45 jaw clutch elements 68 and 69, the latter cast integral with the sprocket wheel 22 and the former splined upon the counter-shaft 67.

The clutch element 68 is brought into 50 operative relation with the jaw 69 by means of the shifting bell-crank lever 70 and the operating rod 71 extending back within reach of the motorman. The two arms of this bell-crank lever are preferably made 55 separate and are held yieldably in right-angled relation to each other by means of the spring 76. In this manner when the locomotive is traveling away from the main entry and the cables are being paid out, 60 provision is made for allowing the clutch element 68 to vibrate axially upon the shaft 67 as its teeth ride over the teeth of clutch element 69 which is held against rotation by the pawl 65.

65 The yieldable friction clutches between

the sprocket wheel 20 and the reel drums, the pawl and ratchet mechanism 64 and 65 and the spiral jaw clutch 75, coöperate in such a manner that when the locomotive is moving away from the main entry the 70 cables unwind from the drums 8 and 9, and a constant tension is yieldably maintained in the cable, while on the other hand when the locomotive is moved in the reverse direction and the cables are being wound upon the reels the same yieldable frictional devices are again utilized to maintain constant tension in the cables.

While I have described a double reel mechanism in order to illustrate one feature 80 of my invention, it is to be understood that one of these reels can be considered as an independent unitary structure in combination with the power transmitting devices and clutch mechanism, and that much of my 85 invention is equally applicable to a locomotive equipped with a single-cable reel.

What I claim is:

1. The combination in an electric locomotive, of two rotatable reels mounted on 90 the locomotive frame, two single conductor cables each secured at one end to one of the reels for winding thereon and each adapted to be connected at its other end to a fixed conductor, and driving mechanism 95 interposed between the locomotive axle and the said reels, the said mechanism tending to drive the said reels to wind the cables at a speed greater than the speed of travel of the locomotive and the mechanism comprising yieldable devices, one for each reel, whereby each reel is enabled to rotate independently of the other at the speed permitted by its own cable.

2. The combination in an electric locomotive, of two rotatable reels mounted on 100 the locomotive frame, two single conductor cables each secured at one end to one of the reels for winding thereon and each adapted to be connected at its other end to a fixed conductor, driving mechanism for the reels 110 comprising two yieldable devices one for each reel, two cable-guide spooling devices, one for each reel, and means for positively 115 gearing each spooling device with its corresponding reel.

3. In an electric locomotive, the combination 120 with a main frame, axles and track wheels upon which the frame is mounted, and a motor operatively connected with the axles and track wheels, of two separate reels mounted on the frame and capable of rotation independently of each other, two electric conductor cables each connected at one 125 end with one reel to be wound thereon and each adapted to be connected at its other end to a fixed electric conductor, and a driving mechanism for the reels comprising a shaft, a clutch capable of transmitting power to rotate the shaft in one direction 130

only, a ratchet and pawl mechanism for preventing rotation of the shaft in the other direction, a friction clutch interposed between the shaft and one of the said reels, and a friction clutch independent of the aforesaid friction clutch interposed between the shaft and the other of the said reels.

4. In an electric locomotive, the combination with a main frame, axles and track wheels upon which the frame is supported, and a motor operatively connected with the axles and track wheels, of two cable reels mounted on the frame and capable of rotation independently of each other, two electric conductor cables each connected at one end to one of the reels to be wound thereon and each adapted to be connected at its other end to a fixed electric conductor, and a driving mechanism for the reels comprising a rotatable power element, means for rotating the power element in one direction only, means for locking the power element against rotation in the other direction, a friction clutch between the power element and one reel, and a separate friction clutch between the power element and the other reel.

5. In an electric locomotive, the combination with a main frame, axles and track wheels for supporting the main frame, and a motor operatively connected with the axles and track wheels to drive them, of two independently rotatable cable reels on the frame, two separate electric conductor cables each connected at one end with one of the reels to be wound thereon and each adapted to be connected at its other end to a fixed electric conductor, a rotatable power element, a connection between one of the axles and the power element for causing it to be rotated in one direction only, means for locking the power element against rotation in the other direction, a friction clutch interposed between the power element and one of the said reels, and a friction clutch separate from the aforesaid friction clutch interposed between the power element and the other of the said reels.

6. In an electric locomotive, the combination with a main frame, axles and track wheels for supporting the main frame, and an electric motor connected with the axles and track wheels to drive them, of two cable reels mounted on the frame each being rotatable independently of the other, two electric conductor cables each connected at one end with one of the reels to be wound thereon and each adapted to be connected at its other end to a fixed electric conductor, a rotatable power element, a power connection between one of the axles and the power element for rotating it in one direction only, means for locking the power element against

rotation in the other direction, a friction clutch between the power element and one of the reels and a separate and independent friction clutch between the power element and the other of the reels.

7. In an electric locomotive, the combination with a main frame, axles and track wheels for the main frame, and a driving motor for the axles and track wheels, of two cable reels mounted in transverse axial alignment on the locomotive frame and capable of rotation independently of each other, a rotatable power element mounted co-axially with the reels and between them, a yieldable connection between the power element and one of the reels, a similar yieldable connection between the power element and the other of the reels, means for driving the power element in a direction to cause rotation of the reels in the winding direction when the locomotive is moving toward the points of attachment of the free ends of the cables, and means for preventing the rotation of the power element in the other direction.

8. In an electric locomotive, the combination with a main frame, axles and track wheels for supporting the main frame, a motor for driving the axles and track wheels, two independent reels mounted in axial alignment on the locomotive frame, two electric conductor cables, each connected at one end with one of the reels to be wound thereon and each adapted to be connected at its other end to a fixed electric conductor, a rotatable power element, a yieldable connection between the power element and one reel, a yieldable connection between the power element and the other reel, means for driving the power element in a direction to cause rotation of the reels in the winding direction when the locomotive is moving toward the points of attachment of the free ends of the cables, means for locking the power element against rotation in the other direction, a cable spooling device positively connected with one of the reels, and an independent cable spooling device positively and directly connected with the other of the reels.

9. In an electric locomotive, the combination with a main frame, axles and track wheels for the main frame, and a driving motor for the axles and track wheels, of two cable reels mounted in transverse axial alignment on the frame and capable of independent rotation with respect to each other, two electric conductor cables, each connected at one end with one of the reels to be wound thereon and each adapted to be connected at its other end to a fixed electric conductor, a rotatable power element mounted co-axially with the reels and between them, a friction connection between the power element and one reel, a friction connection between the power element and the other reel, and a yieldable connection between the power element and the other reel.

other reel, means for driving the power element, two cable spooling mechanisms, one for each reel, means for directly and positively connecting each spooling device with its reel, and a common transverse guide element for both of the spooling devices.

10. In an electric locomotive, the combination with a frame comprising two parallel side pieces, axles and track wheels for the frame, and a driving motor for the axles and track wheels, of two parallel transverse bars extending from one side piece to the other, a cable reeling mechanism mounted on the cross bars for rotation about a transverse axis, and transversely reciprocable cable spooling mechanism mounted on the cross bars adjacent the cable reeling mechanism, one of the cross bars serving as a guide for the spooling mechanism.

11. In an electric locomotive, the combination with a frame comprising two parallel side pieces, axles and track wheels for the frame, and a driving motor for the axles and track wheels, of two parallel transverse bars extending from one side piece to the other, two independently rotatable reels mounted in transverse axial alignment on the two transverse bars, and two transversely reciprocable cable spooling devices, one for each reel, each of the spooling devices being provided with an element which engages with and is guided by one of the cross bars.

In testimony whereof I affix my signature, in presence of two witnesses.
